UNITED STATES PATENT OFFICE

172,630

MICROSCOPE PRISM HOUSING

Michael Macaluso, Jr., Rochester, N. Y., assignor
to Bausch & Lomb Optical Company, Rochester, N. Y., a corporation of New York

Application January 18, 1954, Serial No. 28,548

Term of patent 14 years

(Cl. D57—1)

To all whom it may concern:

Be it known that I, Michael Macaluso, Jr., a citizen of the United States and a resident of Rochester, county of Monroe, and State of New York, have invented a new, original, and ornamental Design for a Microscope Prism Housing, of which the following is a specification, reference being had to the accompanying drawing, forming a part hereof.

Fig. 1 is a side view of a microscope prism housing, showing my new design.

Fig. 2 is an end view thereof.

Fig. 3 is a top plan view thereof.

I claim:

The ornamental design for a microscope prism housing, substantially as shown.
